US00D928081S

(12) **United States Design Patent** (10) Patent No.: **US D928,081 S**
Hwang et al. (45) Date of Patent: **** Aug. 17, 2021**

(54) **POWER SUPPLY UNIT FOR DIGITAL SIGNAGE**

(71) Applicant: **LG ELECTRONICS INC.**, Seoul (KR)

(72) Inventors: **Jungyeon Hwang**, Seoul (KR); **Yongho Lee**, Seoul (KR)

(73) Assignee: **LG ELECTRONICS INC.**, Seoul (KR)

(**) Term: **15 Years**

(21) Appl. No.: **35/508,673**

(22) Filed: **Jun. 3, 2019**

(80) **Hague Agreement Data**

Int. Filing Date: **Jun. 3, 2019**

Int. Reg. No.: **DM/206059**

Int. Reg. Date: **Jun. 3, 2019**

Int. Reg. Pub. Date: **Feb. 28, 2020**

(30) **Foreign Application Priority Data**

Dec. 3, 2018 (KR) 30-2018-0056576
